DIAPER-TYPE GARMENT

Agnes J. Olson, 1243 Woodbridge St., St. Paul, Minn.

Filed Sept. 23, 1957, Ser. No. 685,662

1 Claim. (Cl. 128—287)

This invention relates to a diaper-type garment and more particularly to a combined panty and diaper garment.

The conventional diaper consists of one or more layers of absorbent cloth formed in a rectangular shape and adapted to be folded and pinned on an infant in the well-known manner. The objective of the conventional diaper is that of utility rather than appearance and is not intended to be a garment in the usual sense. There is ordinarily no means for maintaining the outer portion of the diaper in clean and dry condition, and, hence, it has become customary to supply rubber or plastic outer panties to cover the conventional diaper. Such rubber garments likewise are designed primarily for utility and are not particularly dainty or pleasing in appearance. Furthermore, the rubber or plastic often has the objection that it causes irritation or rash on the skin of the infant adjacent the diaper.

When it becomes necessary for an older child to continue wearing diapers, a social problem often arises from the attitude of other children brought about by their awareness of the appearance of the conventional garment. Sometimes the same problem is encountered in hospitals or institutions where it is desirable to furnish adults with a diaper-type garment.

It is, therefore, an important object of this invention to overcome the above noted difficulties and objections in connection with conventional diapers and covering garments, and to provide a comfortable article of wear which has a high degree of utility as a diaper-type garment, yet which presents a neat and pleasing appearance.

Another object of the invention is to provide a pinless combined diaper and panty article which is unfoldable for easy washing and cleaning and is provided with a waterproof insert held in position without the necessity of fastening.

A further object of the invention is to provide a diaper article, the edges of which define an article conforming generally to the contours of a user's legs and waist and which provides the benefits of a diaper while presenting the appearance of a garment for dress wear.

A still further object of the invention is to provide a diaper garment of the class described in which a plurality of fastening elements provide means for progressively and releasably expanding the article so as to properly fit persons requiring such garment irrespective of their body proportions; for example, adult mental patients.

These and other objects and advantages of the invention will more fully appear from the following description made in connection with the accompanying drawings, wherein like reference characters refer to the same or similar parts throughout the several views and in which:

Figure 1 is a view of my invention showing the external side of the diaper panty in extended position;

Figure 2 is a view of my invention showing the internal side of the diaper panty with a waterproof insert and absorbent pad placed in position thereon; portions of

2

the material are cut away to better show the relationship of the parts;

Figure 3 is a view of the insert pad used with my invention;

Figure 4 is a segmental enlarged view taken in section on the line 4—4 of Figure 1, and showing the overlapping relation of the sheet members and the relationship of the tiesstrings to the remainder of the garment;

Figure 5 illustrates the diaper panty of Figures 1 and 2 in secured position on the body of an infant; and

Figure 6 shows an alternate form of pad which is especially adapted for babies during their first few months.

With continued reference to the drawings, my combined diaper and panty garment is shown in front and back view in Figures 1 and 2. The outer exposed area of the garment is indicated generally at 10 and comprises a flexible and absorbent sheet having substantially rectilinear configuration at each end, the ends terminating in edges 11 and 12 respectively, and the side edges adjacent the edge 11 being designated as 13 and 14, while the side edges adjacent the end edge 12 are designated as 15 and 16. The flexible and absorbent sheet 10 has a narrowed area A, the edges of which are smoothly curved at 17 and 18 to define leg openings when the garment is used. The flexible and absorbent sheet 10 may be doubled, tripled, or otherwise constructed in multiple fashion and is designed to have ornamental appearance at the outer exposed area. Thus, outing flannel of plain color or decorative design may be employed as desired. For more utilitarian purposes, such as in institutions, the outer flexible and absorbent sheet may be muslin of plain and neat character or such other cloth and appearance as may suit the circumstances.

I have found it useful to utilize a multiple layer construction in building up the flexible and absorbent sheet 10, particularly so as to produce drawstring passageways which can be simply formed in the stitching together of the layers. It is understood, of course, that I may employ any conventional loops or folds which could accommodate drawstrings and be utilized in the ordinary manner to secure and gather cloth.

In the instant disclosure of Figures 1 and 2, the flexible and absorbent sheet 10 may comprise a layer 19 which defines the entire outer configuration of the garment and a smaller outer layer 20 which can be sewn together with the first layer in a plurality of stitch lines 21 which serve to create passageways 22 and 23 adjacent the respective end edges 11 and 12, passageways 24 and 25 in spaced parallel relation inwardly of the passageways

22 and 23, and drawstring passageways 26 and 27 marginally of the curved edges 17 and 18 which define the narrowed crotch area A. Each of the aforementioned passageways receives a tie or drawstring 28, the outer ends 29 of which extend outwardly beyond the ends of each of the passageways and beyond the rectilinear side edges 13—16. Fixed fasteners such as the snap fastener elements 30 may be applied marginally in predetermined spaced relation along the rectilinear side edges 13 and 14, as shown, and cooperating snap fasteners 31 spaced in the same manner marginally of the rectilinear side edges 15 and 16 at the other end of the garment. The latter fasteners are preferably positioned in alignment with each of the drawstrings 28 for a purpose which will be subsequently disclosed.

In some instances, it is desirable to provide small vent openings 32 at selected areas of the outer sheet, as shown in Figure 1.

An important feature of this invention is means for creating a waterproof barrier internally of the garment and this is accomplished through a flexible and waterproof sheet 33 which may be of exactly the same configuration as the outer sheet 10 and fixed marginally

thereto or may be a loose insert held in position by frictional contact with the inside of the outer sheet 10 and by the particular configuration which tends to maintain it wedged in place. It is useful to have the flexible waterproof sheet 33 fixed marginally or secured directly to the outer sheet 10 at the inwardly facing area thereof so that the surface of the waterproof sheet will provide an area against which other elements of the invention may be inserted and positioned without rumpling the waterproof sheet. I have found that a number of plastic materials, such as polyethylene sheeting, are useful in constructing the flexible waterproof sheet member.

Overlying the flexible waterproof sheet 33 are a pair of panels or sheets 34 and 35 which may be flexible and absorbent and constructed of the same or different material than the outer sheet 10. The overlying panels or sheets 34 and 35 together have substantially the same configuration as the flexible and absorbent sheet, the outer edges being the same and coincident with those of the outer sheet 10. Panels 34 and 35 considered individually conform to a part of the marginal outline of the outer sheet 10 and each has an unsecured edge 36 and 37 which define, in turn, an overlapping flap area 38 on the panel 34 and 39 on the panel 35. Since these overlapping flap portions or areas are unsecured, they produce a pocket opening which permits access to the internal area underlying the panels and interposed between the flexible waterproof sheet 33 and the panel members.

The unit as described above is washable and constitutes a useful garment in itself. I have, however, found it useful to employ auxiliary absorbent pad means in conjunction with the garment and which pad means may be independently separated and cleaned. Such pad is shown separately in Figure 3, and indicated generally at 40. The pad has an end area 41 and an opposed end area 42 with a narrow crotch area 43 which defines a configuration generally similar to that of the garment hitherto described. The pad 40, of course, should have somewhat smaller dimensions for the purpose of easy insertion and removal from between the panel members 34 and 35. The pad element 40 is shown in place in Figure 2 and lies between the absorbent panel members 34 and 35 on the one hand and flexible waterproof sheet 33 on the other hand. The pad 40 may be constructed of absorbent cloth usually employed for diapers and similar garments, and is designed to be soft as well as absorbent and capable of easy cleaning and sterilizing. Although the entire garment may be cleaned with the pad 40 in place, it is understood that washing and cleaning is simplified by separating the pad element 40 from between the flap areas 38 and 39.

Details of the relative positions and marginal sewing as well as the formation of the drawstring passageways is shown in the enlarged cross-sectional view of a segment of the entire device, as shown in Figure 4.

An alternate form of my invention is shown in Figure 6, wherein the outer flexible and absorbent sheet 44 has a general configuration similar to that of sheet 10 in the first form described. Similarly, the garment of Figure 6 is provided with a flexible and waterproof sheet 45 lying against the absorbent sheet 44 and having the same general configuration of the entire garment. Here, again, flexible sheet 45 may be secured to the sheet 44 or may be an independent insert merely held in place by frictional contact. A pair of sheets or panels 46 and 47, together, have substantially the same configuration as the flexible and absorbent sheet 44 and are provided with unsecured overlapping flap areas 48 and 49 respectively. In the instant case, the flexible and absorbent sheet 44 may be usefully built up to a greater degree of thickness and absorbing power so that independent pad means are not required. The device illustrated in Figure 6 may be of the same shape and size as the pad 40 and may be used in the place of pad 40 when inserted into the gar-

ment illustrated in Figures 1 and 2. The garment of Figure 6 may be smaller than that shown in Figures 1 and 2 and may constitute an independent diaper and panty garment for babies during the first few months of their lives. This particular garment of Figure 6 is designed, however, to utilize the flexible and absorbent sheet 44 in contact with the baby's skin and the rectilinear side edges 50 and 51 are designed to be pinned respectively to the rectilinear side edges 52 and 53 with safety pins as is customarily done.

Referring now to Figure 5, the garment of Figures 1 and 2 may be provided with a suitable pad 40, the pad being inserted between the panel flaps 38 and 39 so as to lie intermediate the flexible waterproof sheet 33 and the panels 34 and 35. The device is then applied to the user with the end edges 11 and 12 brought upwardly and the narrowed area A positioned at the crotch. The fixed fasteners 30 are all cooperatively fastened to the respective cooperating fasteners 31 at the side of the user, the intermediate edges 17 and 18 of the garment then surrounding the respective legs of the user. Drawstrings 28 are then drawn up and tied together with corresponding drawstrings so that the adjacent drawstring extensions 29 extending from passageways 22 and 23 are secured together and the respective drawstring extensions 29 extending from the passageways 24 and 25 are similarly tied at their adjacent free ends. The drawstrings 28 in the passageways 26 and 27 respectively are each independently tied together at their own free ends 29, the garment being gathered appropriately. If desired, the side edges 17 and 18 and the upper edges 11 and 12 may be provided with ruffles 54 and 55, respectively. When thus applied, the garment has a pleasing and decorative appearance as well as the usual utilitarian function.

The application and use of the smaller garment shown in Figure 6 and described above will be obvious.

The full utilization of the fasteners and tie or drawstrings of the form of the invention illustrated in Figures 1 and 2 may be made during the training period of a child's life and may obviate the use of independent training garments. In the period prior to training, the garment may be somewhat large for a child and, in such case, that portion of each end of the garment shown in Figure 1 which lies outwardly of the passageways 24 and 25 may be folded over and inwardly with the end portions of panels 34 and 35 being doubled back in self-contact and the tie or drawstrings 28 and fasteners 30 and 31 associated with the passageways 22 and 23 being untied and unfastened if desired. I have found it useful, however, to at least fasten the snap members 30 and 31 when thus using the garment. It will be noted that the passageways 24 and 25 thus become the uppermost edges of the garment and the free ends 29 of the tie or drawstrings 28 thus become the upper fastening elements in conjunction with their aligned and associated fasteners 30 and 31. For smaller children, the drawstrings associated with the respective marginal passageways 26 and 27 may be drawn up more tightly, the cloth gathering to accommodate the 60 situation.

It may thus be seen that I have devised an easily washable garment having all of the utility of the conventional diaper garments together with waterproofing characteristics capable of maintaining rubber, plastic or the like out of contact with the skin of the user, and further providing an ornamental and pleasing appearance which does not suggest the functional aspects of the garment.

It will, of course, be understood that various changes may be made in the form, details, arrangements and proportions of the parts without departing from the scope of my invention.

What I claim is:

A combined diaper and panty garment comprising an elongated exterior flexible sheet having substantially rectilinear end and side portions adjacent each end, said sheet

having a narrowed area intermediate the ends, a flexible waterproof sheet lying inwardly of the exterior sheet and substantially of the same configuration therewith, a pair of inner sheets overlying said flexible waterproof sheet together having substantially the same configuration as the exterior flexible sheet and flexible waterproof sheet and being marginally secured about the entire periphery of the same, said pair of sheets having overlapping flap portions in unsecured relation to each other and in relation to the waterproof sheet, an absorbent pad member lying intermediate the flexible waterproof sheet and said pair of inner sheets, said pad being removable from between the unsecured overlapping portions of said pair of sheets, a pair of drawstrings secured one each along each of the rectilinear end portions and having free ends extending beyond the sides of the garment, a pair of drawstrings secured one each in spaced parallel relation from the rectilinear end portion of the exterior flexible sheet and having free ends extending beyond the side margins thereof, and a separate fixed cooperating pair of fastening ele-

ments secured to the exterior flexible sheet adjacent each of the corresponding pairs of free ends of the drawstrings whereby the garment may be shortened by folding inwardly that portion of the garment lying above each of the spaced second mentioned pair of drawstrings during use.
